UNITED STATES PATENT OFFICE

2,449,907

PICTURE FRAME

Norman E. Olin, New York, N. Y.

Application February 17, 1948, Serial No. 8,870

3 Claims. (Cl. 248—33)

1

This invention relates to improvements in picture frames, and the like, and more especially it pertains to means, or props, for supporting said frames.

A special advantage of my device lies in the construction of said supporting means, whereby the latter is adapted not only to support a frame but may, without being disengaged from said frame and while being permanently connected to the latter, be turned into a position parallel to and in flat engagement with the back of a frame and flush with the latter.

This feature of my device is of great importance when mailing or shipping frames, especially in quantities, as under such conditions the breakage and damage of the supporting means of a frame, which means is generally projecting out from the back of the frame, is quite large, with an incidental financial loss.

With the above and other objects in view, this invention consists of the novel features of construction, combination and arrangement of parts, hereinafter fully described, claimed and illustrated in the accompanying drawings forming part of this application, and in which similar characters of reference indicate corresponding parts in all views, and in which:

Figure 1 is a somewhat perspective plan view of the back of a picture frame, showing my device attached thereto.

Figure 2 is plan elevational side view of Figure 1, but with the frame and support in collapsed position.

Figure 3 is a view similar to Figure 1, showing a slight modification in the construction of my device.

Figure 4 is a view similar to Figure 2, showing the frame in Figure 3.

Referring more particularly to the drawings, the numeral 10 indicates a picture frame.

A block member 11, has on one side 12 thereof substantially flat and secured to the back of the picture frame; the upper portion of said block member is formed with two slanting surfaces 13 and 14, and to one of said surfaces 13 is secured a prop, or supporting member 15, which has one end 16 thereof formed with an oblique surface 17 fitting the surface 13, when the frame is set up. It will appear that the block member 11 is of a substantially triangular shape.

While the block member 11 is fast on the picture frame 10, the prop 15 is turnably attached to said block member as a stud or bolt 18 connects the prop, block member and frame together in the respective manner hereinbefore set forth.

2

When the frame is set up, the prop 15 constitutes a stand-up support for said frame, while, when the prop is turned through an arc of 180 degrees, said prop lies parallel to and in flat engagement with the back of the picture frame, as shown in Figure 2.

A slight modification is shown in Figures 3 and 4, although the features hereinbefore set forth controls the manner of the operation of my device shown in said Figures 3 and 4.

In the latter figures, the numeral 10 indicates the picture frame, which has a block member 11' solidly secured to the back thereof; said block member is of a semirectangular shape, as when a rectangle is cut on a diagonal line.

A prop, or supporting member 15' is turnably arranged on top of said block member 11' and connected to the latter and to the back of the frame 10 by means of a stud, or bolt 18'.

The said prop 15' is at its upper end formed with a portion 20 bent to conform with and lie flat upon the upper surface 13' of the block member 11'; said portion 20 forms at its lower end 21 an obtuse angle with the major portion 22 of the prop 15'.

The operation is here again the same as hereinbefore set forth, as the prop 15' will form a stand-up support for the frame 10, while when the prop is turned through an arc of 180 degrees, said prop will lie parallel to and flat upon the back of the picture frame, as shown in Figure 4.

It is obvious that changes may be made in the form, construction and arrangement of the several parts, as shown, within the scope of the appended claims, without departing from the spirit of the invention, and I do not, therefore, wish to limit myself to the exact construction shown and described herein.

What I claim as new, and desire to secure by Letters Patent of the United States, is:

I claim:

1. A picture frame, a substantially triangular block member fixedly secured to the back of the latter, a prop turnably attached to said block member, and means for securing the picture frame, the block member and the prop together, said prop and block member having their engaging surfaces formed at an angle, whereby the prop, when swung from a position of support through a 180 degree angle, will lie parallel to and in flat engagement with the back of the picture frame.

2. A picture frame, a substantially triangular block member the latter having one flat surface thereof fixedly secured to the back of said frame,

a prop adapted to support the frame and having one end thereof made with a flat slanting surface adapted to engage a correspondingly flat oblique surface of the block member, and a bolt for securing said frame, block member and prop together, the angles of the engaging surfaces of the block member and prop, and relative position with respect to each other being so as to permit the prop, when swung from a position of support through a 180 degree angle to lie parallel to and in flat engagement with the back of said frame.

3. A picture frame, a substantially triangular block member, the latter having one flat surface thereof fixedly secured to the back of said frame,

a prop adapted to support the frame and having one end thereof made with a flat slanting surface adapted to engage a correspondingly flat oblique surface of the block member, and a bolt for securing said frame, block member and prop together, the said prop being at the inner end of its engaging surface with the block member bent to form an obtuse angle, whereby the prop when swung from a position of support through a 180 degree angle, will lie substantially parallel to and in flat engagement with the back of the picture frame.

NORMAN E. OLIN.
